UNITED STATES PATENT OFFICE.

IRVING STANLEY, OF NEW YORK, N. Y., ASSIGNOR TO ANGEL INTERNATIONAL CORPORATION, OF NEW YORK, N. Y., A CORPORATION OF MAINE.

APPARATUS FOR FILLING AND SEALING RECEPTACLES.

Application filed July 9, 1921. Serial No. 483,443.

To all whom it may concern:

Be it known that I, IRVING STANLEY, a citizen of the United States, and a resident of the borough of Manhattan, in the city, 5 county, and State of New York, have invented certain new and useful Improved Apparatus for Filling and Sealing Receptacles, of which the following is a specification.

10 This invention relates to apparatus for filling and sealing containers or receptacles made of paper, such as paraffine paper, said receptacles having an open end which is collapsed and pinched together to close the 15 same and sealed by securing the end in collapsed condition, and it is the principal object of the invention to provide in apparatus of this character receptacle filling means, means to deliver the receptacles from the 20 filling means to a conveyer to support and position the receptacles relative to collapsing and sealing means, and to deliver the filled and sealed receptacles from the conveyer, and to provide apparatus for this 25 purpose which is automatic and efficient in operation.

It is a further object of the invention to provide an improved receptacle carrying conveyer in apparatus of this character, and 30 to means to support a receptacle during the operation of collapsing and sealing of the receptacle to relieve the conveyer of any strains and stresses during the operation of closing and sealing of the receptacle.

35 It is another object of the invention to provide an improved means to collapse the open end of the receptacles to close the same, and provide improved means for arranging a metallic sealing strip with prongs to engage the material of the collapsed end of a 40 receptacle, and to apply the pronged strip to the collapsed end of the receptacle to seal the same.

It is another object of the invention to 45 provide improved means to automatically deliver receptacles from the conveyer after a predetermined number of receptacles have been closed and sealed.

Other objects and advantages will herein 50 after appear.

In the drawings accompanying and forming a part of this specification Figure 1 is a plan view of apparatus illustrating an embodiment of my invention with the receptacle filling means removed.

Figure 2 is a side elevation and showing the receptacle filling means partly in section.

Figure 3 is an end elevation looking at the left of Figure 2.

Figure 4 is a cross sectional view taken on the line 4—4 of Figure 1 to show the receptacle collapsing and sealing means and means to lift a receptacle from the conveyer and present it to said collapsing and sealing means.

Figure 5 is a cross sectional view taken on the line 5—5 of Figure 1 to show the means for delivering the sealed receptacles from the conveyer.

Figure 6 is a perspective view looking at the rear of the receptacle collapsing and sealing means and showing means to feed a sealing strip thereto.

Figure 7 is a perspective view of the collapsed end of a receptacle and showing a clamping and sealing strip in relation thereto.

Figure 8 is a detail view in plan of the means to collapse the open end of a receptacle and to apply a clamping strip to the collapsed end to seal the same and the means to sever the clamping strip, a portion of the clamping strip being shown in operative relation thereto.

Figure 9 is a longitudinal sectional view taken substantially centrally through Figure 8.

Figure 10 is a sectional side elevation of the means to deliver a predetermined quantity of material to a receptacle by the filling means.

Figure 11 is an enlarged sectional plan view of the means for arranging the sealing strip with prongs; and

Figure 12 is a cross sectional detail view taken substantially on the line 12—12 of Figure 11.

Similar characters of reference designate like parts throughout the different views of the drawings.

In carrying out the invention I provide a table or bed B upon which the operative mechanism is mounted, said table being supported by standards S. As stated it is an object of the invention to fill receptacles with material, which may be granulated, or powdered material or liquid, shown in the present instance as consisting of liquid, such as milk, and then to seal the receptacles, the receptacles being made of paper, such as

paraffine paper, consisting of a sheet rolled to tubular form, preferably of truncated conical form with one end, preferably the end of greatest diameter, provided with a closure and the opposite end open and constituting the mouth of the receptacle. A series of such receptacles R, shown as six in number, are placed upon the table in alignment with circular portions of members or abutments 14 fixed in spaced relation upon a slide 15 mounted at opposite ends upon guides 16, the receptacles being positioned in alignment with the outlet of measuring means; (designated in a general way by 17) constituting a part of receptacle filling means to deliver a predetermined quantity of material to the receptacle.

The receptacle filling means comprises a tank 18, having a removable cover 19, to which the material is delivered from a suitable source of supply by a pipe 20 having an outlet leading into the tank, the delivery of the material to the tank being controlled through the pipe by a float controlled valve as shown in a general way at 21. The material is delivered from the tank to the receptacle by dippers 22 (Figure 10) open at the top and normally engaging in cups 23 secured to and projecting downwardly from the bottom of the tank; said cups being arranged with nipples or nozzles 24 carried by tubes 25 extending up centrally through the cups and constituting a continuation of the nipple orifice, said tubes being open at the upper end and upon which the dippers are slidably mounted. The dipper carrying cups are so arranged that when the dippers engage therein the open end of the dippers will be substantially flush or slightly below the bottom of the tank to permit of the flow of the liquid from the tank into the dippers, and to discharge the liquid from the dippers they are raised or lifted to cause the liquid to flow from the dippers through the upper end of the tube 25, and after the liquid has been discharged from the dippers they are again lowered into the cups to receive a further supply of liquid.

To raise and lower the dippers they are connected by rods 26 to a crank shaft 27 (Figure 2) journaled in the opposite side walls of the tank and rotated by a crank arm 28 fixed to a projecting end on the shaft, said crank arm being actuated by a cam 29 on a shaft 30 and operatively connected to the cam by a link 31. The shaft 30 is driven from a shaft 32 through a pinion 33 (Figures 1 and 2) on said shaft meshing with a gear 34 on a countershaft 35, and a pinion 36 on said latter shaft meshing with a pinion 37 on shaft 30. The shaft 32 is driven from a suitable source of power, shown as an electric motor M having a worm fixed to the shaft thereof meshing with a worm wheel 38 loose on the shaft 32 and op-

eratively connected to the shaft through a clutch, one member 39 of the clutch being integral with the worm wheel and the other member 40 mounted on the shaft 32 to rotate therewith and have sliding movement thereon, said clutch member 40 being thrown into and out of operative connection with the clutch member 39 by the bifurcated end of an arm 41 engaging an annular groove in the clutch member 40, said arm being fixed to a slidably supported actuating rod 42.

The receptacles are, after being filled, transferred from the table or receptacle support to a conveyer to be transported to means to collapse and seal the open end of the receptacles. This conveyer comprises a pair of sprocket chains 43 passing in parallel and spaced relation around sprocket wheels 44, 45 fixed to shafts 46, 47 journaled in hangers fixed to the end supporting standards S of the frame-work. Receptacle supporting sides in the form of plates 48 are successively arranged upon the chains to extend transversely thereof and are pivotally connected to the pivot pins of the chain links, said plates having upwardly turned flanges 49 at the leading and trailing ends and a central perforation 50 for a purpose to be hereinafter described. The conveyer is intermittently advanced predetermined distances by a ratchet wheel 51 fixed to shaft 47 with which a ratchet pawl 52 pivotally carried by an arm 53 hung on the shaft 47 co-operates. The pawl is actuated by a cam 54 on shaft 32 through a pivoted lever 55 carrying a roller at one end to co-operate with the cam 54, the other end being connected to the pawl carrying arm 53 by a link 56.

The receptacles are delivered from the table or receptacle support to the receptacle seats 48 on the conveyer by the movement of the slide 15, this slide being reciprocated by a pair of arms 58 fixed to a rock shaft 59 (Figure 3) the arms having bifurcated ends for the engagement of fingers 60 fixed to and extending laterally from the slide. Rocker arms 58 are actuated by a cam 61 on the shaft 30 through a link 62 pivotally connected to one of the arms and carrying a roller to co-operate with the cam.

The ratio of rotation between the shaft 32 and the shaft 30 is six to one whereby six intermittent movements will be imparted to the conveyor to one receptacle transferring movement of the slide 15, and the dippers of the receptacle filling means, the movement of the dippers being alternate with the movement of the receptacle transferring slide. By this arrangement six intermittent movements will be imparted to the conveyer whereby six receptacle receiving seats of the conveyer will be positioned relative to the receptacle supported in relation to the receptacle fill-

ing means permitting of a sufficient lapse of time for the replenishing of the receptacles to the receptacle filling means and without any interruption in the actuation of the conveyer.

The receptacles are successively positioned by the conveyer relative to receptacle collapsing and sealing means mounted upon the table or bed B in juxtaposed relation to the receptacle filling means and above the receptacles on the conveyer. The receptacle collapsing means comprises a pair of heads or slides 64, 65 slidably mounted in a slide-way 66 mounted upon or integral with a fixture 67 (Figure 6) mounted upon the table or bed B. The slides or heads are normally maintained in opposed and spaced relation as shown in Figure 2, and the receptacles are positioned with the open end 10 between said heads during the periods of rest of the conveyer. For this purpose a plunger 68 is carried by a bracket 69 (Figure 4) fixed to the frame work to extend downwardly and forwardly between the 15 stretches of one of the conveyer chains with the plunger located in the space between the chains of the conveyer to have vertical sliding movement in the bracket and relative to which plunger the perforations in the receptacle supporting plates of the conveyer are 20 adapted to be aligned to permit of the movement of the plunger through said perforations to engage the bottom of a receptacle supported upon a receptacle seat and to lift 25 it from the conveyer to position the open end of the receptacle between the collapsing heads or slides. After the open ends of the receptacles have been collapsed and sealed the plunger is receded to seat the receptacle 30 upon a receptacle seat of the conveyer. To reciprocate the plunger pins extending from opposite sides of the plunger slidably engage in slots in the plunger support and in bifurcations at the ends of arms 70, as shown at 35 71, Figure 4. To reciprocate the plunger the arms 70 are fixed to and project forward from a rock shaft 72, said shaft being rocked by a cam 73 on shaft 32 through a link 74 carrying a roller to co-operate with the cam 40 and connected to an arm 75 on the shaft 72.

To reciprocate the collapsing slides 64, 65, arms 76, 77 pivotally supported upon the bracket 67 have bifurcated ends for the engagement of pins projecting upward from the slides, as shown at 78, 79, the arms being connected by a link 80 in such a manner that as one of the levers is moved to move one slide in one direction the other slide will be operated in opposed relation. The slides 45 are actuated from a cam 81 on shaft 32 by a link 82 carrying a cam following roller and connected to an arm 83 fixed to the pivotal support of the arm 76. The cam 81 operates to reciprocate the slides toward 50 and away from each other and after the

slides have been moved away from each other the plunger 68 is actuated to again re-seat the receptacle upon the receptacle support of the conveyer. To maintain the receptacle in position between the collapsing 55 slides during the collapsing movement thereof a guide or gauge is provided to engage at opposite sides of the receptacle. This gauge comprises a supplemental slide 84 slidably carried below the slide member 65 and normally urged by a spring 86 in a direction to extend beyond the receptacle collapsing face of said head with said end of the supplemental slide bifurcated to provide the gauge fingers 85, as shown in Figure 8.

Simultaneously with the collapsing movement of the heads 64, 65, the clamping strip 87 arranged with prongs stamped therefrom is applied to the collapsed end with the prongs of the strip piercing the material of the closure and upset thereby sealing and retaining the collapsed end of the receptacle in collapsed condition. This strip is intermittently fed in interposed relation to the collapsing heads from a roll 88 (Figure 1) 60 with a portion of the strip engaging a seat extending forward of the head 64 as shown in Figure 8. This seat is formed by a supplemental slide 89 slidably carried below the head 64 and normally urged to extend a pre-determined distance beyond the receptacle collapsing face of said head by a spring 90. As the heads 64, 65 are moved relative to each other to collapse the open end of a receptacle, as shown in Figure 9, the engagement of the supplemental slide 89 with the side of the receptacle will force said slide rearwardly against the action of its spring 90. Simultaneously with the collapsing of the receptacle and the applying of the sealing strip thereto the portion of the strip to seal the receptacle is severed by cutting mechanism comprising a blade 91 slidably carried by the head 65 and normally urged outward from said head, said blade co-operating with a cutter member 92 carried by the head 64.

To intermittently feed the strip to the collapsing heads 64, 65 a pair of positively driven feeding rollers 93, 94 rotatably carried by the bracket 67 are provided. The wheel 94 is arranged with peripheral grooves for the passage of the prongs of the sealing strip. The feeding wheels are intermittently rotated by pawl and ratchet mechanism comprising a ratchet wheel 95 fixed to a stud shaft 96 in the fixture 67 and a co-operating pawl 97 pivotally carried by an arm 98 hung on the shaft 96, the pawl carrying arm being actuated by a cam 99 on 115 shaft 32 operatively connected to the arm by a link 100 arranged with a cam follower. The movement of the ratchet wheel is transmitted to the feed wheels through a gear 120 101 rotatable with the ratchet wheel mesh- 125 130

1
ing with a pinion 101' on the shaft of wheel 93, and a gear 102 on said latter shaft meshing with a pinion 102' rotatable with the wheel 94.

5 As the collapsing heads 64, 65 are moved toward each other to collapse the open end of the receptacle R, as shown in Figures 7 and 9, the cutter 91 is actuated to sever the sealing strip by a cam 103 on shaft 32 through a cam follower carrying rod 104 pivotedly connected to an arm 105 fixed to a shaft 106 rotatably mounted in the bracket 67 (Figure 6), said shaft carrying a second arm 107 having a bifurcated end to engage pins projecting from the cutter, as shown at 108.

Alternately with the feeding of the clamping or sealing strip 87 the strip is provided with sealing prongs by punch and die mechanism interposed between feeding wheels 93, 20 94 and the strip roll 88, as shown in a general way at 109 in Figure 1. This punch and die mechanism comprises a die member 110 fixed in a recess portion of a fixture 111 fixed to the bed B, said die member having a longitudinal recess of two widths with the portion of less width at the bottom and having a series of alined and spaced pins 113 fixed therein and a perforated plate 114 arranged in the portion of greatest width in superposed relation to the pins, the perforations in said plate being positioned in line with the spaces between the pins with the portion of the recess of reduced width forming a seat for said plate. Plates 115 are fixed to the outer side of the die member to overhang the recess forming gibs to retain and guide the clamping strip between said plates and the perforated plate 114. A punch consisting of a head 116 is slidably mounted in the recess of the fixture 111 in opposed relation to the die member 110 and to have movement toward and away from said member, said head carrying a series of 45 alined punches 117 in alinement with the perforations in the die plate 114, a perforated stripping plate 118 being carried by the punch with the perforations in register with the punches and normally urged outward toward the ends of the pins by springs 119. The punch is reciprocated through a lever 120 (Figure 1) pivotally supported upon the die fixture and carrying a roller to co-operate with a cam 121 on the shaft 32, 55 the lever being connected to the punch head by a plunger 122.

The receptacles after being sealed and returned to the conveyer are positioned by the intermittent movement of the conveyer relative to means to deliver or eject the sealed receptacles from the conveyer to a tray T which may be removably supported upon a shelf 123 carried by the frame-work. This delivery means comprises a slide 124 slidably supported at opposite ends by guide

members 125 fixed upon the bed B, abutments 126 being fixed upon said slide and having a rounded portion for the engagement of the receptacles on the conveyer. The slide is reciprocated transversely of the movement of the conveyer by a rock shaft 127 rotatably mounted at one end in the end standard S and at the opposite end in a hanger 128 fixed to the bottom of the bed B, said shaft being connected to the slide by arms 129 fixed to said shaft having bifurcated ends in which engage fingers 130 fixed to and extending laterally from the slide. The shaft 127 is rocked by a cam 131 on shaft 30 operatively connected to the shaft by a rod 132 pivotedly connected to an arm 133 of the rock shaft. The receptacle delivery slide is operable during a period of rest of the conveyer, and the operation of the slide is timed to have one movement imparted thereto to six intermittent movements of the conveyer whereby as the delivery slide is actuated six receptacles on the conveyer will be positioned in alinement with the abutments 126 on the delivery slide to be engaged by said abutments as the slide is actuated.

Having thus described my invention I claim:

1. In apparatus of the class specified, the combination of receptacle filling means including a support for a series of receptacles; receptacle collapsing and closure applying means; an intermittently movable conveyer arranged as receptacle supporting seats to transport receptacles from the filling means to the closure means; means to transfer the receptacles from the support of the receptacle filling means to the receptacle supporting seats of the conveyer during the periods of rest of the conveyer; and means to present a receptacle from the conveyer relative to the closure applying means for action thereon by the latter during the periods of rest of the conveyer.

2. In apparatus of the class specified, the combination of receptacle filling means arranged to deliver a predetermined quantity of material simultaneously to a series of receptacles; an intermittently movable conveyer arranged with perforate receptacle seats relative to which the receptacles are positioned to transport the receptacles from the filling means; means to transfer the receptacles from the filling means to the receptacle seats on the conveyer; receptacle collapsing and closure applying means; and means operable during the periods of rest of the conveyer to engage the receptacles through the perforations in the seats, lift the receptacles from the conveyer and present the same relative to the closure applying means and return the same to the conveyer after the closure has been applied thereto.

3. In apparatus of the class specified, the combination of receptacle filling means in-

- cluding a support for a series of receptacles; receptacle collapsing and closure applying means; an intermittently operable conveyer arranged as receptacle supporting seats to transport the receptacles from the filling means to the closure means; means to deliver a series of receptacles simultaneously from said support of the filling means to the receptacle supporting seats of the conveyer during a period of rest of the latter; and means operable during the periods of rest of the conveyer to successively lift the receptacles from the conveyer and position the same relative to the closure applying means for action thereon by the latter and return the receptacles to the conveyer after the closure has been applied thereto.
4. In apparatus of the class specified, the combination of receptacle filling means; receptacle collapsing and closure applying means; an intermittently movable conveyer to transport the receptacles from the filling means to the closure means; means to deliver a series of receptacles simultaneously from the filling means to the conveyer during a period of rest of the latter; means to lift the receptacles successively from the conveyer and position the same relative to the closure means for action thereon by the latter during the periods of rest of the conveyer; and means to deliver a series of the closed receptacles simultaneously and laterally from the conveyer during a period of rest of the latter.
5. In apparatus of the class specified, an intermittently movable receptacle conveyer; a pair of opposed slides in superposed relation to the receptacles on the conveyer reciprocable toward and away from each other and relative to which a receptacle on the conveyer is arranged to be positioned during the periods of rest of the conveyer; means to feed a clamping strip in interposed relation to said slides; means to lift a receptacle from the conveyer and position it with the open end between said slides; and means to move said slides to collapse the open end of the receptacle and apply the clamping strip thereto to secure the receptacle in collapsed and closed condition; and said receptacle lifting means being operable to reposition the receptacle upon the conveyer for the purpose specified.
6. In apparatus of the class specified, an intermittently movable receptacle conveyer; a pair of slides supported in opposed and superposed relation to a receptacle on the conveyer and adapted to have reciprocable movement toward and away from each other; means to feed a clamping strip in interposed relation to said slides; means to move the receptacle successively from the conveyer and position the same with the open end engaging between the slides; means to move said slides relative to each other to collapse the open end of the receptacle and apply the clamping strip thereto to retain the collapsed end of the receptacle in closed condition, said slides being provided with means to position the receptacle between the slides during the receptacle collapsing movement of the slides; and means to sever the portion of the clamping strip retaining the receptacle in collapsed condition.
7. In apparatus of the class specified, an intermittently movable conveyer arranged with successive perforated receptacle supports; means to collapse the open end of the receptacle to close said end and apply a clamping strip thereto to retain the receptacle in collapsed and closed condition; a vertically slidable plunger operable to engage a receptacle on the conveyer to lift the same from the receptacle support and position them relatively to the receptacle collapsing means and return them to position on the conveyer during the periods of rest of the conveyer.
8. In apparatus of the class specified, an intermittently movable receptacle conveyer, means arranged in a plane above the receptacles on the conveyer to which the receptacles on the conveyer are successively presented to collapse the open end of the receptacles, comprising a pair of opposed slides reciprocable toward and away from each other; a pivoted lever connected to each of said slides; a rod connecting said levers; a rod connected to one of said levers; a rotatable cam; a cam follower carried by the rod; and means to feed a clamping strip in interposed relation to the slides, and the fed portion of the clamping strip being adapted to be severed and applied to the collapsed receptacle to retain it in its collapsed condition.
9. In apparatus of the class specified, an intermittently movable receptacle conveyer, means arranged in a plane above the receptacles on the conveyer to which the receptacles on the conveyer are successively presented to collapse the open end of the receptacles, comprising a pair of opposed slides reciprocable toward and away from each other; means to reciprocate the slides; a supplemental slide carried below one of the receptacle collapsing slides to have longitudinal movement thereof and normally urged to a predetermined position beyond the end of said slide to form a seat for a clamping strip; a supplemental slide carried by the other receptacle collapsing slide to have longitudinal movement thereof and having a bifurcated end, said slide being normally urged to position with the bifurcated end extending beyond the end of the slide and adapted to retain the receptacle between the collapsing slides during the receptacle collapsing movement thereof; means to feed a clamping strip to the clamp-

ing strip supporting seat, said clamping strip being adapted to be applied to the receptacle by the receptacle collapsing slides as the slides are moved to receptacle collapsing position; and cutting mechanism carried by the collapsing slides to sever the fed clamping strip.

10. In apparatus of the class specified, an intermittently movable receptacle conveyer; 10 a pair of slides arranged in opposed and spaced relation and relative to which the receptacles on the conveyer are successively positioned, said slides being reciprocable relative to each other to collapse the open 15 end of a receptacle and apply a clamping strip thereto to secure the receptacle in collapsed condition; and means to provide a metallic strip with prongs and feed said strip in interposed relation to the receptacle 20 collapsing slides.

11. In apparatus of the class specified, an intermittently movable receptacle conveyer; a pair of slides arranged in opposed and spaced relation and relative to which the 25 receptacles on the conveyer are successively positioned, said slides being reciprocable relative to each other to collapse the open end of a receptacle and apply a clamping strip thereto to secure the receptacle in collapsed condition; means to intermittently and alternately with the receptacle collapsing movement of the slides feed a predetermined portion of the clamping strip in interposed relation to said slides; and means 30

operable during the periods of rest of the 35 clamping strip feeding movements to stamp portions of the strip therefrom to provide the strip with prongs.

12. In apparatus of the class specified, an intermittently movable receptacle conveyer; 40 a pair of slides arranged in opposed and spaced relation and relative to which the receptacles on the conveyer are successively positioned, said slides being reciprocable relative to each other to collapse the open 45 end of a receptacle and apply a clamping strip thereto to secure the receptacle in collapsed condition; a pair of rollers operable alternately with the receptacle collapsing movement of the slides to feed a clamping strip in 50 interposed relation to the slides; and means operable during the periods of rest of the clamping strip feeding rollers to stamp portions of the strip therefrom to provide the 55 strip with prongs, comprising a fixed member arranged with series of aligned and spaced pins, a plate carried by said member having perforations in alignment with the spaces between the pins, and a head movement toward and away from the pin carrying 60 member arranged with a series of punches in alignment with the perforations in the blade.

Signed at New York city, in the county of New York and State of New York, this 5th 65 day of May, 1921.

IRVING STANLEY.
